UNITED STATES PATENT OFFICE.

WILLIAM MILLEN DUNCAN, OF ALTON, ILLINOIS.

IGNITION-ARCH FOR FURNACES.

1,027,326.

Specification of Letters Patent.

Patented May 21, 1912.

Application filed August 18, 1911. Serial No. 644,733.

To all whom it may concern:

Be it known that I, WILLIAM M. DUNCAN, a citizen of the United States of America, residing at Alton, in the county of Madison 5 and State of Illinois, have invented certain new and useful Improvements in Ignition-Arches for Furnaces, of which the following is a full, clear, and exact description, reference being had to the accompanying 10 drawings, forming part of this specification.

My invention relates to that character of arches used in furnaces for the promotion of the combustion of fuel called ignition arches. Arches of this description commonly 15 comprise pluralities of rows of heat radiating blocks mounted on suitable supports to which they are fitted in a manner to permit the ready mounting of the blocks and their removal when they become impaired. 20 Paired by subjection to heat in the furnace. It is a fact well known that the heat radiating blocks at the rear ends of the ignition arches become impaired much more rapidly than do the blocks in front of them, 25 and also that when such impairment of the rearmost blocks occurs, there is frequently, if not usually, such impairment of the block supporting members as to render them unfit to receive new blocks it may be desired 30 to substitute for those that have become impaired.

The object of my present improvement is to provide in connection with the main block supporting members of an ignition arch auxiliary 35 block supporting members adapted to receive the rearmost heat radiating blocks, and which auxiliary supporting members are separable from the main supporting members, thereby making it possible 40 to replace them by similar auxiliary supporting members when those previously in use have become unserviceable.

Figure I is a view partly in side elevation and partly in longitudinal section of an 45 ignition arch containing my improvement, the view also including portions of a furnace and mechanical stoker in dotted outline. Fig. II is a top or plan view of my ignition arch with portions of the arch in 50 horizontal section. Fig. III is an enlarged perspective view of one of the auxiliary block supporting members and a fragment of one of the main block supporting members, the parts being shown separated from 55 each other.

In the accompanying drawings:—A and

B designate the transversely arranged heat radiating blocks of my ignition arch, the blocks A being those entering into the structure of the arch throughout its main and front end while the blocks B are those located at the rear end of the arch, and which are the most liable to become injured or impaired by the greater heat they are subjected to as compared with the heat to which the remainder of the blocks are subjected. 60 The heat radiating blocks are provided with longitudinal perforations extending therethrough and they are arranged in rows extending longitudinally above the furnace 70 grate. The longitudinal perforations *a* in the blocks A receive main supporting rods 1 on which the blocks A are threaded. The main block supporting rods are shown in the drawings, (see Figs. I and II), of tubular form, and they are preferably made of this form to permit circulation of air therethrough in order that the rods will withstand greater heat than they would without circulation of air through them. The main 75 supporting rods are suspended from suitable supports, such as beams 2, by suitable hangers 3 held in engagement with the beams in any suitable manner. The longitudinal perforations *b* in the heat radiating 80 blocks B receive auxiliary supporting rods 4 that are removably connected to the main supporting rods A. These auxiliary supporting rods are preferably tubular to permit circulation of air therethrough with the same object in view as that sought in making the main supporting rods tubular. Each auxiliary block supporting rod is provided with a reduced inner end providing a stem 85 5, of less diameter than the body of the rod and which extends forwardly from a shoulder 6 on the rod. The auxiliary supporting rods 4 are connected to the main supporting rods 1 by slipping the stems 5 of the former into the latter until the shoulders 6 of the auxiliary supporting rods abut against the rear ends of the main supporting rods, as seen in Fig. II, subsequently to which the auxiliary supporting rods 4 will remain in alinement with the main supporting rods 1 and the joined supporting rods will serve as units for the support of heat radiating blocks mounted thereon.

It will be noted on referring to Fig. II 110 that the main block supporting rods 1 project only to the rearmost blocks A and that

consequently should the auxiliary supporting rods 4 be so impaired by heat as to be rendered unfit for use, the rear portions of the main supporting rods 1 are not subjected to a sufficient degree of heat to impair them, and they therefore remain in serviceable condition to receive new auxiliary supporting rods. Therefore, when there is occasion for replacement of the rearmost 10 blocks B and the auxiliary supporting rods supporting them, such replacement may be readily carried out by the simple acts of removing the blocks B, the auxiliary supporting rods, and the substitution of new 15 auxiliary supporting rods and new blocks B.

I claim:

1. An ignition arch comprising longitudinally arranged tubular main supporting rods located at the front end of the arch, 20 heat radiating blocks mounted on said main supporting rods, longitudinally arranged

auxiliary supporting rods having reduced ends and located at the rear end of the arch and having their reduced ends inserted in said main supporting rods, and heat radiating blocks mounted on said auxiliary supporting rods. 25

2. An ignition arch comprising longitudinally arranged tubular main supporting rods located at the front end of the arch, 30 heat radiating blocks mounted on said main supporting rods, longitudinally arranged tubular auxiliary supporting rods having reduced ends and located at the rear end of the arch and having their reduced ends inserted in 35 said main supporting rods, and heat radiating blocks mounted on said auxiliary supporting rods.

WILLIAM MILLEN DUNCAN.
